UNITED STATES PATENT OFFICE

2,465,225

POLISHING WHEEL

Urban C. Haren, Akron, Ohio, assignor to The
B. F. Goodrich Company, New York, N. Y., a
corporation of New York

Application February 27, 1946, Serial No. 650,396

1 Claim. (Cl. 51—194)

1

This invention relates to polishing wheels and is especially useful in the polishing of flat surfaces.

Objects of the invention are to provide a succession of cushioned polishing members for engaging the work, to provide renewability of the polishing surfaces, and to provide spring support for the polishing members.

These and other objects will appear from the following description and the accompanying drawings.

Of the drawings:

Fig. 1 is an end elevation, partly broken away and in section showing the invention in one of its forms.

Fig. 2 is a cross-section thereof taken on line 2—2 of Fig. 1.

Fig. 3 is a detail sectional view thereof taken on line 3—3 of Fig. 1.

Fig. 4 is a view similar to Fig. 1 showing another form of my invention, and

Fig. 5 is a longitudinal sectional view thereof, taken on line 5—5 of Fig. 4.

Referring to the drawings, and first to Figs. 1 to 3 thereof, the numeral 10 designates a shaft about which a tubular driving support 11 is rotatably mounted, as on ball bearings 12, 13 and 14. The shaft 10 is fixed to a stationary arm 15. The support 11 has a sprocket 16 fixed thereto for driving it.

The tubular support 11 has a flange 17 fixed to one end thereof and a similar flange 18 is removably mounted on the other end thereof where it is held against axial movement by a fixed shoulder 19 and a collar 20, the collar having threaded engagement with the tubular support.

Flanges 17 and 18 have aligned apertures 21, 22 at spaced-apart positions thereabout for rotatably supporting a plurality of rods 23 arranged parallel to the shaft 10.

Each rod has fixed thereto a polishing member 25 having limited swinging movement with its rod and member extending therealong. Coil springs 26, 27 seated in radial sockets of flanges 18, 17 respectively impinge against the polishing members 25 and force them radially outward while L-shaped rods 28 fixed to the polishing members engage under the next successive rods and limit outward movement.

Each polishing member supports a strip of flexible sheet abrasive material 30, such as emery cloth, sandpaper, or the like which is fixed to the rod 23 as by a clamp bar 31 held in place by screws 32, the abrasive strip being secured only

2

at one edge and extending freely along the outer face of the polishing member.

For cushioning the abrasive strip, a pad 33 of resilient rubber-like material such as soft vulcanized rubber, synthetic rubber or the like is fixed to the polishing member 25 by a vulcanized bond and underlies the abrasive strip.

In use, the polishing members are forced outwardly by the springs 26, 27 and also by centrifugal force, and the abrasive strips are pressed against the work and cushioned by the cushions 33.

Referring to the form of the invention illustrated in Figs. 4 and 5, a stationary shaft 50 rotatably supports a tubular support 51 which is rotatably mounted thereupon by ball-bearings 52, 53. The support is adapted to be driven by a sprocket 54 fixed thereto.

The support 51 has a fixed flange 55 at one end thereof and a removable flange 55a at its other end. Flange 55a is secured thereon between a fixed shoulder 56 and a collar 57 screw-threaded to the shaft.

Flanges 55, 55a are formed with aligned apertures 58, 59 respectively at spaced-apart intervals thereabout in which rods 60 are pivotally mounted. Each rod 60 has arms 61 extending therefrom and secured at their outer ends to a rod 62 parallel to rod 61. A pad 63 of resilient rubber-like material such as soft vulcanized rubber encloses the rod 62 and the arms 61 to cushion the abrasive material. The ends of rods extend beyond the resilient cushion and engage in slotted openings 64, 65 through the flanges 55, 55a which limit swinging movement of the polishing members.

Endless bands 66 of flexible abrasive material, such as emery cloth, sandpaper or the like encompass the polishing members individually and may be removed and replaced endwise thereover when the removable flange 55a is removed.

For tensioning the bands about the polishing members while urging the polishing members radially outward, a rod 70 is provided and extends parallel to the axis of the shaft 50. Leaf springs 71 have one end secured to the tubular support 51 and the opposite end secured to the rod 70 to urge it toward the polishing element. One rod 70 is provided at each cushioning pad.

In use the endless bands of abrasive material are held against excessive slipping about the polishing members by pressure of the rods 70 thereagainst while the springs 71 also urge the polishing members outwardly against the work assisted by centrifugal force. Outward movement is lim-

ited by the slots 64, 65 in which the ends of rods 62 are located.

Variations may be made without departing from the scope of the invention as it is defined by the following claim.

I claim:

A polishing wheel comprising a rotatable support having spaced apart radial flanges, one flange being removably secured thereto, said flanges having aligned apertures therethrough at spaced apart positions thereabout, rods pivotally retained in said apertures, each rod having a relatively stiff polishing shoe secured thereto and adapted to swing arcuately thereof, a pad of resilient rubber-like material secured to said shoe for supporting and cushioning a strip of abrasive sheet material, spring means for urging said shoe

outwardly, and means for limiting movement of said shoe, said spring means including means for retaining said abrasive sheet material on said shoe.

URBAN C. HAREN.
